INTEGRATING COUNTER

William C. Grabau, San Francisco, Calif.

Application February 6, 1950, Serial No. 142,692

12 Claims. (Cl. 235—92)

1

This invention relates to counters, and in general has for its object the provision of an integrating counter for effecting a group count of a plurality of events or operations such as for example the movement of a plurality of objects past a given point or station.

Counters for this purpose are desirable in many industries. Stationary, for example, is sold in bundles designated as reams, there being 480 sheets to a short ream, 500 sheets to a long ream and 516 sheets to a printer's ream. The sheets are continuously delivered from a cutter or a press and although there are counters available for effecting a progressive count thereof, the problem is to integrate this count into counts representing reams and/or to operate some sort of translating device such as a signal either on the group count or on a predetermined individual count preceding each group count.

More or less the same problem is presented when it is desired to stack shingles in bundles each containing a predetermined and selected number of shingles, or in numerically segregating any other objects into groups.

More specifically the object of this invention is the provision of an integrating counter comprising: a control circuit including a power release relay and responsive to an external translating device, which in turn is responsive to the movement of each object of a plurality of objects to be counted in groups of a preselected number; a locked torque, shaded pole, reversible type motor having a rotor, a main winding arranged to be continuously energized during the entire counting operation, and a pair of shading coils arranged to be alternately short-circuited to reverse the direction of rotation of said rotor at each group count; a power escapement or release mechanism associated with the shaft of the motor and operable in response to the power release relay for permitting said shaft to rotate in predetermined increments; a pair of rotatable dials each graduated in 100 units, one of said dials being designated as a units dial and the other as a hundreds dial; a pair of gear trains driven by said motor and in driving relation with said dials, there being a differential in the gear ratios of these gears such that when the units dial has completed one revolution the hundreds dial has rotated through only 99 of its 100 units; one fixed and one adjustable switch cam mounted on each of said dials for rotation therewith; a pair of stationary switches associated with each of said dials and located in the path of its cams so as to be periodically closed in response to the

2

movement thereof; and an electric circuit including said cam actuated switches, a vernier switch periodically closing in response to the rotation of said shaft, a set of interlocking relay switches, one of said switches being operable to alternately short-circuit said shading coils and open and close a controlled circuit in response to a pre-selected sequence of operation of said cam actuated switch, said controlled circuit being arranged to be connected with any desired external translating device such as a conventional magnetic counter, bell, light or relay switch.

The invention possesses other advantageous features, some of which, with the foregoing, will be set forth at length in the following description where that form of the invention which has been selected for illustration in the drawings accompanying and forming a part of the present specification is outlined in full. In said drawings, one form of the invention is shown, but it is to be understood that it is not limited to such form, since the invention as set forth in the claims may be embodied in a plurality of forms.

Referring to the drawings:

Fig. 1 is an elevational view of the back side of an integrating counter embodying the objects of my invention.

Fig. 2 is a fragmentary front elevation of the counter illustrated in Fig. 1.

Fig. 3 is a vertical section taken on the section line 3—3 of Fig. 1.

Fig. 4 is a vertical section taken on the section line 4—4 of Fig. 1.

Fig. 5 is a vertical section taken on the section line 5—5 of Fig. 1.

Fig. 6 is a section taken on the section line 6—6 of Fig. 3.

Fig. 7 is an enlarged section of the power release mechanism illustrated in Fig. 4.

Fig. 8 is a wiring diagram showing the electrical circuit associated with and forming a part of the counter shown in the above figures.

Figs. 9, 10, 11 and 12 are front elevations of the counter panel progressively showing the condition of the dials in counting from zero to the predetermined count of 710 and back again to the count of 1420.

Figs. 9a, 10a and 11a are schematic wiring diagrams showing the condition of the electrical circuit corresponding to the positions of the dials shown respectively in Figs. 9, 10 and 11.

As shown in the figures above described, my counter comprises an instrument panel 1 provided with suitable screw holes 2 at its corners for fastening it to a suitable instrument case,

not shown. Mounted on the rear face of the panel by brackets 3 and 4 is a locked torque, shaded pole, reversible type motor 5 of conventional construction. The motor 5 includes a rotor 6 provided at its ends with axially aligned drive shafts 7 and 8 terminating respectively in four-thread worms 9 and 11. As diagrammatically illustrated in Fig. 8, the motor 5 also includes an electromagnet 12 provided with a field coil 13 and shading coils 14 and 15.

Fastened to the panel 1 by screws 16 are a pair of parallel sleeves 17 and 18 (see Figs. 3 and 4), and mounted in each of these sleeves are a pair of bearing bushings 19 and 21, the bushing 19 extending forwardly through the panel 1. Journaled in the bearings 19 and 21 of the sleeve 17 is a shaft 22 and similarly journaled in the bearing bushings of the sleeve 18 is a shaft 23. Fastened to the shaft 22 by a set screw 24 is a worm gear 25 having 100 teeth and arranged to mesh with the four-thread worm 9 and similarly fastened to the shaft 23 is a worm gear 26 having 101 teeth and arranged to mesh with the four-thread worm 11. Since the gear 25 is provided with one hundred teeth and its associated worm 9 is provided with four threads, the gear ratio between these two members is 1 to 25. In other words, each complete revolution of the worm 9 serves to advance the worm gear 25 by four teeth or a quarter revolution of the worm serves to advance the worm gear 25 by one tooth. The diameter of the worm gear 26 should be sufficiently greater than the diameter of the worm gear 25 to result in a gear ratio between these two members of 100 to 99. As a result of this gear ratio differential, the worm gear 26 will complete only 99/100 of a revolution for each complete revolution of the gear 25.

Fastened to each of the shafts 22 and 23 immediately forward of its associated bearing bushing 19 is a spacing washer 27. Journaled on the shaft 22 immediately forward of its spacing washer 27 by means of a flanged bearing bushing 28 is a units dial 29, the dial 29 having a press fit with the bushing 28. Threaded over the forward end of the shaft 22 is a knurled lock nut 31 for locking the dial 29 to the shaft 22 in any desired angular position relative thereto. Similarly journaled on the forward end of the shaft 23 by a flanged bushing 32 is a hundreds dial 33 arranged to be locked to the shaft 23 in any desired angular position relative thereto by a knurled lock nut 34. Provided on the faces of each of the dials 29 and 33 respectively are continuous scales 35 and 36, each divided or graduated into one hundred units, the scale 35 being designated for purposes of convenience as the units scale and the scale 36 being designated as a hundreds scale. The scale 35 is therefore a function of the scale 36 and although for purposes of illustration the decimal system has been used, any other system can be resorted to so long as one scale is a predetermined function of the other scale.

Fixed to the back of the units dial 29 is a cam pin 37 having a rounded end. Adjustably mounted on the rear face of the dial 29 is a cam pin 38, this cam being mounted on a peripherally adjustable slide 39 provided with pins 41 arranged to travel in a circular channel 42 formed in the back face of the dial.

Attached to the forward side of the slide 39 by a screw 43 is a plate 44 overhanging the outer periphery of the dial. Threaded in the slide 39 is a set screw 45 for affixing the slide to the dial

in any predetermined angular position relative thereto. From an inspection of Fig. 3 it is to be noted that the cam pin 38 is radially offset with respect to the fixed cam pin 37, and from an inspection of Fig. 2 it will be noted that it can also be adjusted to assume any desired angular position relative to the cam pin 37.

The dial 33 is similarly provided with a fixed cam pin 46 and with a peripherally adjustable cam pin 47 mounted on a slide 48, a set screw 49 being provided on the slide for fastening it in any predetermined selected position relative to its dial 33. Mounted on the back of the panel 1 at either end thereof are microswitches 51 and 52, these switches being shown in dotted line in Fig. 1, and the switch 51 being shown in full line in Fig. 5. As shown in Fig. 5, each of these microswitches includes an actuator arm 53 pivoted to the switch body and provided on its free end with a cam follower roll 54. The cam follower rolls extend through openings 55 formed in the panel 1 and are disposed in the path of the fixed cam pins 37 and 46. The microswitches 51 and 52 are of conventional construction and provided with spring means for biasing their actuating arms 53 outwardly in the paths of the cam pins 37 and 46. As a result of this construction, whenever either of the cam pins passes over its associated cam follower roll 54 the corresponding microswitch will be closed.

Inscribed on the base of the panel adjacent each of the dials 29 and 33 are fiducial marks 56 and 57 respectively, the location of the microswitches 51 and 52 relative to their associated cam pins 37 and 46 being such that when these pins serve to close their associated microswitches 51 and 52 the zero positions of these dials are in registration with their respective fiducial marks 56 and 57.

Fastened to the back of the panel 1 behind the dial 29 is a conventional microswitch 58 in all respects similar to microswitches 51 and 52 and including a cam follower roll 59 (see Figs. 1 and 3). The roller 59 extends through a hole 61 formed in the panel and is located in the locus of the peripherally adjustable cam pin 38. It will therefore be seen that whenever the cam pin 38 passes over the cam follower roller 59 the switch 58 will close momentarily. Similarly mounted on the panel 1 behind the dial 33 is a conventional microswitch 62 provided with a cam follower roll 63 as shown in dotted line in Fig. 1. The cam follower 63 extends through an opening in the panel 1 and is located in the locus of the adjustable cam pin 47 so that whenever the cam pin 47 engages this roll the switch 62 will be closed momentarily.

Mounted on the back side of panel 1 beneath the worm 11 is a conventional electromagnet 65 power relay 66 including a relay coil 66 and an armature 67 pivoted to the relay body by a pin 68. Fixed to the armature 67 at substantially right angles thereto is a switch actuator 69. Carried by the relay are a pair of spaced switch contacts 72 and 73 and an intermediate contactor 74 carried on a spring finger 75. With the switch actuator 69 in its upper position as shown in Fig. 8 the contacts 72 and 74 are in engagement with each other with the contact 73 disengaged from the contact 74. Upon depression of the contactor 69 due to the inward movement of the armature 67 when the relay coil 66 is energized, the actuator 69 closes the contact 74 on the contact 73 and breaks the contact between the contacts 72 and 74.

Formed on or secured to the free end of the armature 67 is an escapement or power release finger 76 extending upwardly to a point immediately adjacent the shaft 8 and disposed between two longitudinally spaced collars 77 and 78 fastened to the shaft 8. Carried by the collar 77 are four inwardly extending escapement studs 79 spaced 90° apart with respect to each other and similarly carried by the collar 78 are four inwardly extending studs 81 also spaced 90° apart with respect to each other and angularly offset 45° with respect to the angular location of the studs 79. Normally the spring finger 75 holds the power escapement finger 76 outwardly in the position shown in Fig. 1, the finger 76 then being located between two adjacent studs 79. When the relay coil 66 is energized, the finger 76 moves to the right (as viewed in Fig. 1) to a position between two of the adjacent studs 81. This mechanism therefore serves as a clutch, escapement or power release for permitting the shafts 7 and 8 to rotate only through $\frac{1}{8}$ of a revolution when the finger 76 is in either of one of its two positions, this being more clearly illustrated in Fig. 7. In this figure, the finger 76 is shown stopped by one of the studs 79. Upon the inward movement of the finger 76 when the power relay coil 66 is energized, it will move to a position between the two adjacent studs 81 and after the shaft has moved through $\frac{1}{8}$ of a revolution it will be stopped by the adjacent stud 81. As previously described, $\frac{1}{4}$ of a revolution of the shafts 7 and 8 will cause the worms 9 and 11 to displace the gear 25 through one tooth and the gear 26 through somewhat less than one tooth.

Mounted on the switch 51 is a conventional interlocking reversing relay generally designated by the reference numeral 85 (see Fig. 5), and including a pair of relay coils 86 and 87, a pair of armatures 88 and 89, and a double throw switch generally designated by the reference numeral 91. The armature 88 is pivoted to the relay by a pin 92 and is formed with a right angularly extending switch arm 93 provided with a switch actuator 94. The double throw switch 91 (see Figs. 1 and 5) includes a common contactor 95 supported by a spring finger 96 and two adjacent contacts 97 and 98. Mounted respectively on the armatures 88 and 89 and movable therewith are interlocking arms 99 and 101. When the relay coil 86 is energized its armature 88 moves inwardly and the arm 93 moves outwardly thereby moving the switch actuator 94 outwardly to close its contact 95 on the outer contact 98. In accordance with well known operation, the interlocking arm 101 moves behind the end of the arm 99 so as to lock the relay in this position until such time as the armature coil 87 has been energized. Upon the occurrence of this event the armature 89 will move inwardly to release the arm 101 from beneath the end of the arm 99 thereby permitting the switch actuator 94 to move inwardly to open the contacts 95 and 98 and to close the contact 95 on the contact 97.

Also mounted on the switch 85 adjacent the contacts 95, 97 and 98, but insulated therefrom, are a pair of contacts 102 and 103 the back ends of which are shown in Fig. 1 and which are diagrammatically indicated in Fig. 8. These contacts are adapted to be brought into engagement with each other in response to the downward movement of the actuator 94. Similarly mounted on the switch 52 is a conventional reversing relay generally designated by the ref-

erence numeral 104, including a pair of relay coils 105 and 106, a pair of armatures 107 and 108, a pair of interlocking arms 109 and 111, a pair of contact points 112 and 113, and a switch actuator movable in response to the movement of the armature 107 for closing the contact point 112 on the contact point 113 (also see Fig. 8).

As diagrammatically indicated in Fig. 8, the movable contact points of the switches 51 and 58 are connected respectively through leads 115 and 116, and a common lead 117, with the contact point 72 of the power release relay 65. The fixed contact point of the switch 51 communicates through a lead 118 with a vernier switch generally designated by the reference numeral 119, and through leads 119a and 120 with the movable contacts of the switches 52 and 62, respectively.

The fixed contact of the switch 52 communicates through a lead 121 with one of the terminals 122 of the relay coil 106 and with one of the terminals 123 of the relay coil 86. The fixed terminal of the switch 62 communicates with one end of the relay coil 105 through a lead 124. The fixed terminal of the switch 58 communicates through a lead 125 with the contact point 113 of the relay switch 103, the other contact point of the switch 103 communicating through a lead 126 with one of the terminals 127 of the relay coil 87. The relay coils 86 and 105 are connected in parallel through the leads 128 and 129, the terminals 131 and 132 of the relay coils 86 and 87 being connected to the lead 128.

The lead 128 communicates with one of the terminals 133 of the motor field coil 13, the other terminal 134 of this coil communicating through a lead 135 with the contact 102 of the switch 91. The coil terminal 134 also communicates through the lead 135 with one of the terminals 136 of an on-and-off switch generally designated by the reference numeral 137 and mounted on the lower edge of the panel 1. The other contact point 138 of the switch 137 communicates through a lead 139 with a lead 141 communicating with the terminal 133 of the coil 13 and also with the terminals 142 of a conventional magnetic counter 143. As shown in Fig. 2 the counter 143 is mounted on the panel 1 with its face visible through a window 144 formed in the panel. The other terminal 145 of the magnetic counter communicates through a lead 146 with the terminal 73 associated with the switch of the power release relay 65.

The on-and-off switch 137 serves to establish communication between the device above described and the positive and negative terminals of a power line generally designated by the reference numeral 147. Connected to the terminal 163 of the relay switch 85 is a lead 148 communicating with the positive terminal 149 of a translating device such as a bell, light, switch or conventional magnetic counter to be actuated under the influence of the circuit above described. The negative side of any device of this character can of course be connected to the negative side of the line 148 to complete the circuit. Connected to one of the terminals 151 of the coil 66 of the power release relay 65 is a lead 152 communicating through a lead 153 with the contact 74 of the switch associated with the relay 65 and communicating with the terminal 134 of the coil 13.

The other terminal 154 of the coil 66 communicates through a lead 155 with the positive

terminal 156 of any translating device such as a switch directly or indirectly operable under the influence of the objects to be counted in groups in accordance with the object of my invention. The other terminal of such translating device can of course be connected with the negative side of the power line 147 to complete the circuit.

The vernier switch 119 interposed between the switches 51 and 52 is a microswitch of the same type as the switches 58 and 62 and includes a cam follower roll 157. Detachably mounted on the shaft 7 by a set screw 158 is a collar 159 extending radially from this collar is a cam pin 161 in alignment with the roll 157, the roll 157 being located in the locus of the pin. As a result of this structure the switch 119 assumes its closed position momentarily only once during each complete revolution of the shaft 7. It should here be noted that this switch is actuated directly in response to the rotation of the shaft 7 whereas the cam pins 37, 41, 46 and 47 are driven indirectly through the gear trains constituted by the worms and worm gears associated with the shafts 7 and 8. Therefore the interposition of the vernier switch 119 between the switch 51 and the switches 52 and 62 ensures that the circuits including the leads 121 and 124 will be energized directly in timed relation with the rotation of the shaft regardless of inaccuracies or back-lash in the gear trains.

Operation

For the purposes of illustrating the operation of the device above described, let it be assumed that it is desired to effect a count of 710 and each succeeding multiple thereof. More specifically, let it be assumed that it is desired to energize the controlled translating device connected with the terminal 149 each time that the controlling translating device connected with the terminal 156 has been energized 710 times. The knurled lock nuts 31 and 34 serving to fasten the dials 29 and 33 to their respective shafts are loosened and the zero points of the dials are respectively brought into registration with the fiducial marks 56 and 57 inscribed on the panel. As shown in Fig. 8, this will serve to close the switches 51 and 52. The clip 39 of the unit dial is then adjusted and locked so that its fiducial mark 39a lies over the number 10 of the scale 35 and similarly the clip 48 of the dial 33 is adjusted and locked so that its fiducial mark 48a lies over the number 7 of the scale 36. Also at this time the vernier switch 119 should be closed by so adjusting the collar 159 that its cam pin 161 is in direct engagement with the cam follower roll 157. The on-and-off switch 137 can then be closed whereupon the circuit will assume the condition shown in Fig. 8. Since in this condition of the circuit the relay coils 86 and 106 are energized, the armatures 88 and 108 of the relays 85 and 104 will be in their closed position and held in these positions by the interlocking arms 101 and 111 of their associated relays. Since the contact 96 of the reversing relay 85 is now in engagement with the contact 91, the shading coil 14 is short circuited and consequently the motor 6 will rotate in a counter-clockwise direction whenever permitted to do so by the escapement mechanism associated with the power release relay 65. Since the external translating device connected to the terminal 149 is under the control of the switch actuator 94 of the relay 85 the condition of this translating device will remain unchanged until the armature 88 of the relay 85 is permitted to move upwardly

and this can occur only when the relay coil 87 is energized. However, the coil 87 is under the control of the switch 103 of the relay 104 and consequently the upward movement of the armature 88 will occur only when the coil 105 of the relay 104 is energized. From an inspection of Fig. 8 it will be seen that the coil 105 can be energized only provided that the switches 51, 119 and 62 are all simultaneously in their closed positions. When the coil 66 of the power release relay 65 is energized under the influence of the controlling translating device connected to the terminal 156 and which in turn is responsive to the movement of the objects to be counted, the movable contact 74 will close on the contact 13 thereby closing the circuit including the magnetic counter 143 and opening the circuits including the switches 51, 52, 58, 62 and 119. When the external control circuit associated with the terminal 156 is broken, the movable contact 74 of the power release relay switch 65 will return to its normal position in contact with the contact point 72.

During this single complete cycle of operation of the power release relay its associated finger 76 will have moved first to the right as shown in Fig. 1 to thereby permit the shafts 7 and 8 to rotate through $\frac{1}{2}$ of a revolution and then to the left to its original position thereby to permit the shafts to rotate through an additional $\frac{1}{2}$ of a revolution to complete a single count. Simultaneously the counter 143 will have effected a single count, this being indicated on its face. The dials 29 and 33 will each have moved one unit counter-clockwise, it being borne in mind that the gear ratio between these two dials is 100 to 99. Upon the initial movement of the shafts 7 and 8 the switches 51, 52 and 119 will open and although this serves to deenergize the relay coils 86 and 106, their armatures 88 and 108 will nevertheless remain in their closed positions due to the interlocking action of the arms 101 and 111. The motor 6 will therefore continue to rotate in a counter-clockwise direction step-by-step in increments corresponding to $\frac{1}{2}$ of a revolution under the influence of each make and break of the switch associated with the power release relay 65 until the coil 87 of the relay 85 is energized.

Referring now to Figs. 9 and 9a, it will be seen that when the units dial 29 has completed one revolution its zero mark will be in registration with the fiducial mark 56 and the switch 51 will again be in its closed position as indicated in Fig. 9a. The hundredths dial 33 will be short one unit from arriving at its initial position and consequently the switch 52 will remain open. Although the vernier switch 119 is closed at this point, the switches 52 and 62 are open and consequently the condition of the relays 85 and 105 is unchanged and the motor will continue to rotate in a counter-clockwise direction.

The first change taking place in the circuit serving to influence either of the relays 85 and 104 occurs at the count of 700 as indicated in Figs. 10 and 10a. At the end of this count the zero point of the units dial 29 is in registration with the zero fiducial line 58, and the fiducial line 48a of the slide 48 will be in registration with the fiducial line 57 which insofar as the circuit is concerned means that the switches 51, 119 and 62 are closed, whereupon the relay coil 105 is energized and the switch 103 is closed. However, at this point no current can flow through the relay coil 87 for the reason that at this count the switch 58 is still in its open position. So far, all

that has happened is that the armature 107 has been drawn into its closed position and locked in that position by the locking arm 109 of its associated relay. Upon the completion of the count of 710 the dials and circuits are in the condition shown in Figs. 11 and 11a with the fiducial line 39a of the slide 39 in registration with the fiducial line 56 of the panel.

The switch 51 is now in its open position, the switch 58 is closed, and the switch 62 is in its open position. The circuit through the relay coil 87 has therefore been completed and consequently the armature 89 will be drawn downwardly and locked in its closed position by the arm 99, and the armature 88 has moved to its open position. Simultaneously with the movement of the armature 88 to its open position the switch actuator 94 has moved outwardly to break the connection between the contacts 102 and 103, to break the connection between the contacts 96 and 97 and to close the movable contact 96 on the contact 98. This results in shorting out the shading coil 15, breaking the closed circuit including the shading coil 14, and breaking the circuit including the lead 148 and the terminal 149. The breaking of this latter circuit actuates the controlled translating device connected to the terminal 149 and which as previously stated may take the form of a counter, bell, light or any other suitable device. If a counter is used it will indicate a count of 1 whereas the counter 143 will have registered a total count of 710.

The motor 6 will now rotate in a clockwise direction until the first multiple of the count of 710 (1420) has been reached, whereupon the motor will again reverse so as to rotate in a counter-clockwise direction. Upon each reversal of the direction of rotation of the motor the externally controlled translating device connected with the terminal 149 will be actuated. If the external translating device is in the form of a counter it will register a count for each movement of the switch actuator 94.

During the entire operation of the device, the vernier switch 19 closes and opens during each revolution of the shafts 7 and 8. The dimensions and contour of the cam pin 61 serving to actuate the vernier switch should be such that the switch remains closed for an interval of time equivalent to $\frac{1}{8}$ of a count. Although this switch makes and breaks once during each revolution of the shafts, this is of significance only during such periods that the switches 51, 52 and 62 are closing. During these periods of operation, the vernier switch serves to ensure that the circuits controlled by the switches 52 and 62 are energized within a time period having no greater variation than that represented by $\frac{1}{8}$ of a count, regardless of minor inaccuracies in the gear trains resulting either from their manufacture or wear.

The use of a reversible motor greatly simplifies an integrating counter of this type for upon arriving at each count the sequence of operation of the switches 51, 52, 58 and 62 is simply reversed with the consequent reversal of the sequence of operation of the relay switches 85 and 104. Any integrating counter not making use of this expedient would certainly require a greater number of dial actuated switches and would in all probability involve other complications.

I claim:

1. An integrating translating device comprising: a motor; a shaft driven by said motor; means for actuating said motor to rotate said shaft step by step in predetermined increments

in either direction; means responsive to each rotation of said shaft through a predetermined number of said increments in one direction for causing said shaft to rotate in the opposite direction through a like number of predetermined increments; and means responsive to the reversal of rotation of said shaft for controlling a controlled translating device circuit, said latter means including a first switch actuator dial 10 driven by said shaft step by step in n_1 increments for each complete revolution of said dial and a second switch actuator dial driven by said shaft step by step in n_2 increments for each complete revolution of said second dial where $n_1 - n_2$ is an integer.

2. An integrating translating device comprising: a locked torque, shaded pole reversible type motor including a shaft and a pair of shading coils; means including an escapement mechanism associated with said shaft for actuating said motor to rotate said shaft step by step through a predetermined number of equal increments in either direction; means including a relay switch responsive to each rotation of said shaft through said predetermined number of increments in one direction for simultaneously shorting out one of said shading coils and opening the other of said shading coils to reverse said motor and cause said shaft to rotate step by step in the opposite direction through a like number of predetermined intervals; and means including said relay switch, responsive to each reversal of said motor for controlling a controlled translating device circuit.

3. An integrating translating device comprising: a controlling circuit including a controlling circuit switch and a controlling circuit relay for actuating said switch; a controlled circuit including a controlled circuit switch; a locked torque, shaded pole, reversible type motor including a shaft, a main armature coil in circuit with a source of power and first and second shading coils in circuit respectively with first and second shading coil switches; an escapement mechanism associated with said shaft for constraining said shaft to rotate in either direction step by step in predetermined equal increments, said escapement mechanism being under the control of said controlling circuit relay; a controlled circuit relay, said controlled circuit switch and said shading coil switches being under the control of said controlled circuit relay; and an intermediate circuit including a plurality of sequentially operating switches in circuit with said controlling circuit switch and with said controlled circuit relay, said sequentially operating switches being under the control of said shaft to open and close in a predetermined sequence.

4. An integrating translating device comprising: a controlling circuit including a controlling circuit switch and a controlling circuit relay for actuating said switch; a controlled circuit including a controlled circuit switch; a locked torque, shaded pole, reversible type motor including a shaft, a main armature coil in circuit with a source of power and first and second shading coils in circuit respectively with first and second shading coil switches; an escapement mechanism associated with said shaft for constraining said shaft to rotate in either direction step by step in predetermined equal increments, said escapement mechanism being under the control of said controlling circuit relay; a controlled circuit relay, said controlled circuit switch and said shading coil switches being under the control of said controlled circuit relay; an intermediate

circuit including a plurality of sequentially operating switches in circuit with said controlling circuit switch and with said controlled circuit relay; and a dial operated by said shaft and provided with a plurality of switch actuators for sequentially closing said sequentially operating switches.

5. An integrating translating device comprising: a controlling circuit including a controlling circuit switch and a controlling circuit relay for actuating said switch; a controlled circuit including a controlled circuit switch; a locked torque, shaded pole, reversible type motor including a shaft, a main armature coil in circuit with a source of power and first and second shading coils in circuit respectively with first and second shading coil switches; an escapement mechanism associated with said shaft for constraining said shaft to rotate in either direction step by step in predetermined equal increments, said escapement mechanism being under the control of said controlling circuit relay; a controlled circuit relay, said controlled circuit switch and said shading coil switches being under the control of said controlled circuit relay; an intermediate circuit including first and second pairs of sequentially operating switches in circuit with said controlling circuit switch and with said controlled circuit relay; a first dial rotating in response to the rotation of said shaft in n_1 equal increments to each complete revolution of said first dial, said first dial being provided with a first pair of switch actuators for sequentially closing said first pair of sequentially operating switches; and a second dial rotating in response to the rotation of said shaft in n_2 equal in increments to each complete revolution of said second dial, said second dial being provided with a second pair of switch actuators for sequentially closing said second pair of sequentially operating switches, and n_1-n_2 being an integer.

6. An integrating translating device comprising: a controlling circuit including a controlling circuit relay; a controlled circuit including a controlled circuit switch; a shaft; means including a motor for rotating said shaft in either direction; an escapement mechanism associated with said shaft and under the control of said controlling circuit relay for constraining said shaft to move in either direction step by step in predetermined increments; and intermediate circuit including a first switch under the control of said controlling circuit relay, a controlled relay for actuating said controlled circuit switch and a plurality of intermediate switches; means responsive to the rotation of said shaft for actuating said intermediate switches in a predetermined sequence thereby periodically to actuate said controlled relay; and means responsive to the operation of said controlled relay for reversing the direction of rotation of said shaft.

7. An integrating translating device comprising: a controlling circuit including a controlling circuit relay; a controlled circuit including a controlled circuit switch; a shaft; means including a motor for rotating said shaft in either direction; an escapement mechanism associated with said shaft and under the control of said controlling circuit relay for constraining said shaft to move in either direction step by step in predetermined increments; an intermediate circuit including a first switch under the control of said controlling circuit relay, a controlled relay for actuating said controlled circuit switch, and second, third and fourth switches connected in series with each other, in series with said first

switch and in series with said controlled relay; means responsive to a selected multiple n_1 of the incremental movement of said shaft for actuating one of said second, third and fourth switches; additional means responsive to selected multiples n_2 and n_3 of the incremental movement of said shaft for selectively actuating the remaining two of said second, third and fourth switches thereby momentarily to close said intermediate circuit each time that said shaft has advanced m increments, m being a predetermined selected function of n_1 , n_2 and n_3 ; and means under the control of said intermediate circuit for reversing the direction of rotation of said shaft each time that it has rotated through m increments.

8. An integrating translating device comprising: a controlling circuit including a controlling circuit relay; a controlled circuit including a controlled circuit switch; a shaft; means including a motor for rotating said shaft in either direction; an escapement mechanism associated with said shaft and under the control of said controlling circuit relay for constraining said shaft to move in either direction step by step in predetermined increments; an intermediate circuit including a first switch under the control of said controlling circuit relay, a controlled relay for actuating said controlled circuit switch, and second, third and fourth switches connected in series with each other, in series with said first switch and in series with said controlled relay; a first switch actuator driven by said shaft and responsive to a selected multiple n_1 of the incremental rotation of said shaft for actuating one of said second, third and fourth switches; and second and third switch actuators driven by said shaft and responsive respectively to selected multiples n_2 and n_3 of the incremental movement of said shaft for selectively actuating the remaining two of said second, third and fourth switches thereby momentarily to close said intermediate circuit each time that said shaft has rotated m increments, m being a predetermined selected function of n_1 , n_2 and n_3 .

9. An integrating translating device comprising: a controlling circuit including a controlling circuit relay; a controlled circuit including a controlled circuit switch; a reversible motor including a shaft and motor reversing means; an escapement mechanism associated with said shaft and under the control of said controlling circuit relay for constraining said shaft to rotate in either direction step by step in predetermined equal increments; an intermediate circuit including a first switch under the control of said controlling circuit relay, a controlled relay for actuating said controlled circuit switch and also said motor reversing means, and second, third and fourth series connected switches connected in series with said first switch and with said controlled relay; means responsive to a selected multiple n_1 of the incremental rotation of said shaft for actuating one of said second, third and fourth switches, and additional means respectively responsive to selected multiples n_2 and n_3 of the incremental rotation of said shaft for selectively actuating the remaining two of said second, third and fourth switches thereby momentarily to close said intermediate circuit each time that said shaft has rotated through m in increments, m being a predetermined selected integer function of n_1 , n_2 and n_3 .

10. An integrating translating device comprising: a controlling circuit including a con-

trolling circuit relay; a controlled circuit including a controlled circuit switch; a reversible motor including a shaft and motor reversing means; an escapement mechanism associated with said shaft and under the control of said controlling circuit relay for constraining said shaft to rotate in either direction step by step in predetermined equal increments; an intermediate circuit including a first switch under the control of said controlling circuit relay, a controlled relay for actuating said controlled circuit switch and also said motor reversing means, and second, third and fourth series connected switches connecting in series with said first switch and with said controlled relay; a first switch actuator driven by said shaft and responsive to a selected multiple n_1 of the incremental rotation of said shaft for actuating one of said second, third and fourth switches; and second and third switch actuators driven by said shaft and responsive respectively to selected multiples n_2 and n_3 of the incremental movement of said shaft for selectively actuating the remaining two of said second, third and fourth switches thereby momentarily to close said intermediate circuit each time that said shaft has rotated m increments, m being a predetermined selected function of n_1 , n_2 and n_3 .

11. An integrating translating device comprising: a controlling circuit including a controlling circuit relay; a controlled circuit including a controlled circuit switch; a locked torque, shaded pole, reversible type motor including a shaft, a main field coil, and a pair of shading coils; an escapement mechanism associated with said shaft and under the control of said controlling circuit relay for constraining said shaft to rotate in either direction step by step in predetermined equal increments; an intermediate circuit including a first switch under the control of said controlling circuit relay, a controlled relay for actuating said controlled circuit switch, and second, third and fourth series connected switches connected in series with said first switch and with said controlled relay; means responsive to a selected multiple n_1 of the incremental rotation of said shaft for actuating one of said second, third and fourth switches; additional means respectively responsive to selected multiples n_2 and n_3 of the incremental rotation of said shaft for selectively actuating the remaining two of said second, third and fourth switches thereby momentarily to close said intermediate circuit

each time that said shaft has rotated through m increments, m being a predetermined selected and integer function of n_1 , n_2 and n_3 ; and shading coil switches in circuit with said shading coils and under the control of said controlled relay for alternately shorting out said shading coils upon each rotation of said shaft through m increments to thereby reverse said motor at each count of m .

10 12. An integrating translating device comprising: a controlling circuit including a controlling circuit relay; a controlled circuit including a controlled circuit switch; a shaft; means including a motor for rotating said shaft in either direction; an escapement mechanism associated with said shaft and under the control of said controlling circuit relay for constraining said shaft to move in either direction step by step in predetermined increments; an intermediate circuit including a first switch under the control of said controlling circuit relay, a set of interlocking relays for actuating said controlled circuit switch, and first and second sets of sequentially operating switches in circuit with said first switch and with said interlocking relays; a first set of switch actuators responsive to the rotation of said shaft for sequentially actuating said first set of sequentially operating switches; a second set of switch actuators responsive to the rotation of said shaft for sequentially actuating said second set of sequentially operating switches; and means under the control of said controlled relay for reversing the direction of rotation of said shaft.

WILLIAM C. GRABAU.
